Primary Examiner—Cathron Brooks*Assistant Examiner*—Austin Murphy(74) *Attorney, Agent, or Firm*—Wesley W. Muller(57) **CLAIM**

The ornamental design for a multi-tool, as shown and described.

DESCRIPTION

FIG. 1 is a front perspective view of a multi-tool according to the present invention;

FIG. 2 is a rear perspective view of a multi-tool of FIG. 1;

FIG. 3 is a top view of the multi-tool of FIG. 1;

FIG. 4 is a bottom view of the multi-tool of FIG. 1;

FIG. 5 is a right side view of the multi-tool of FIG. 1;

FIG. 6 is a left side view of the multi-tool of FIG. 1;

FIG. 7 is a rear view of the multi-tool of FIG. 1; and,

FIG. 8 is a front view of the multi-tool of FIG. 1.
